(57) **CLAIM**

The ornamental design for a high voltage control box, as shown and described.

DESCRIPTION

1. High voltage control box

1.1 : Front

1.2 : Back

1.3 : Left

1.4 : Right

1.5 : Top

1.6 : Bottom

1.7 : Perspective

Portions shown in broken lines illustrate elements of the high voltage control box which form no part of the claimed design.
